Patented Feb. 5, 1957

179,640

COMBINED CLOSURE CAP AND POURING SPOUT

Richard E. Hartung, Rumson, and Cleonard F. Harms,
East Keansburg, N. J., assignors to Plastics Manufacturing Inc., Orange, N. J., a corporation of New Jersey

Application April 5, 1956, Serial No. 40,923

Term of patent 14 years

(Cl. D58—26)

Fig. 1.

Fig. 2.

Fig. 1 is a top plan view of a combined closure cap and pouring spout, embodying our new design, and Fig. 2 is a side elevational view thereof.

We claim:

The ornamental design for a combined closure cap and pouring spout, as shown.
